UNITED STATES PATENT OFFICE.

WILLIAM ROBERTSON, OF BUFFALO, NEW YORK.

DESIGN FOR A BATH-TUB SEAT.

SPECIFICATION forming part of Design No. 29,993, dated January 10, 1899.

Application filed December 9, 1898. Serial No. 698,784. Term of patent 14 years.

To all whom it may concern:

Be it known that I, WILLIAM ROBERTSON, a citizen of the Dominion of Canada, residing at Buffalo, in the county of Erie and State of New York, have invented and produced a new and original Design for Bath-Tub Seats, of which the following is a specification, reference being had to the accompanying drawing, forming part thereof.

10 The figure is a perspective of a bath-seat showing my new design.

As shown in the drawing, the leading or material feature of my design consists of the arms A A, which extend outward from each 15 end of the seat B, are bent upward at a, di-

verge outward at b, and curve downward at c, and under said curved portion of the arms is a pad or support C, concavo-convex in transverse section and elliptical in plan view.

Having described my invention, what I claim as new, and desire to secure by Letters Patent, is—

The design for a bath-seat, substantially as herein shown and described.

In testimony whereof I affix my signature 25 in presence of two witnesses.

WILLIAM ROBERTSON.
